DESCRIPTION

FIG. 1 is a top, front, and right side perspective view of a bottle;

FIG. 2 is a front elevational view thereof, the back elevational view being a mirror image;

FIG. 3 is a left side elevational view thereof, the right side elevational view being a mirror image;

FIG. 4 is a top plan view thereof; and,

FIG. 5 is a bottom plan view thereof.

The broken line showing in FIGS. 1-5 are included for the purpose of showing environmental structure that forms no part of the claimed design.
